UNITED STATES PATENT OFFICE.

JOHN ASHCROFT, OF NEW YORK, N. Y.

FURNACE FOR STEAM-BOILERS.

SPECIFICATION forming part of Letters Patent No. 356,675, dated January 25, 1887.

Application filed May 29, 1886. Serial No. 203,625. (No model.)

To all whom it may concern:

Be it known that I, JOHN ASHCROFT, a citizen of the United States, residing at New York, in the county of New York and State of New York, have invented certain new and useful Improvements in Furnaces for Steam-Boilers, of which the following is a specification, reference being had therein to the accompanying drawings.

10 My invention relates to improvements in grates for the furnaces of steam-boilers, the object of which is to utilize the heat of the furnace for heating the water before it enters the boiler.

15 My invention consists of the alternate arrangement of hollow water-bars with solid movable bars of the grate, said solid bars being adapted to be revolved, as will more fully appear.

20 My invention consists, further, in certain details of construction, which will be fully described hereinafter, and pointed out in the claim.

Figure 1 is a longitudinal vertical sectional view of the furnace and one of the water-bars. Fig. 2 is a horizontal sectional view of the furnace on the line *xx* of Fig. 1. Fig. 3 is a sectional end view of the same on the line *yy* of Fig. 2. Fig. 4 is a top or plan view of a modification. Fig. 5 is a horizontal sectional view, on an enlarged scale, of the water-tubes and water box or back. Fig. 6 is a sectional view on the line *zz* of Fig. 5.

Referring to drawings, A designates the side 35 wall of the furnace; B, the bridge-wall; C, the front wall with openings D for the furnace doors and like openings, E, to the ash-pit.

F are bearing-bars, arranged at suitable distances apart for the support of the grate-bars, said bearing-bars being provided with notches *a*, to receive the grate-bars and prevent them from being laterally displaced while being shaken or revolved to free the fire of clinkers or ashes.

40 G are solid grate-bars supported on the bearing-bars F, said bars being, by preference, of triangular shape in cross-section, as this form of bar is superior to all others in that it lasts longer and is easily turned in its bearings, 45 while the angular portions serve to cut or break

the clinker which may have formed in the furnace. This form of bar was patented to me November 27, 1877, No. 197,510, and need not be more fully described in this connection.

H are hollow or water grate-bars, which, by 55 preference, are made of heavy wrought-iron pipe or tubing, the front ends of which are closed by screw-caps I, while the rear ends are connected to and communicate with the hot-water chamber K of the water-back L, and by 60 providing the hollow bars H with screw-caps I am enabled to have ready access to the interior of said bars and to the water-back, to clean the same from dirt or scales when required. These hollow bars are arranged alternately between the solid triangular bars G, and are provided with small open-ended tubes M, located therein, said tubes M being connected to and communicating with the cold-water chamber N of the water-back L.

70 L is the water inlet and outlet chamber, located in the bridge-wall B of the furnace, and consists of a cast-iron rectangular box divided into two longitudinal compartments, K and N, by the partition O. The chamber or compartment N is connected to a suitable cold-water-supply tank by means of the pipe P, while the chamber K is connected to the boiler by means of the pipe R.

75 In Fig. 3 I have shown a modification in which the water-bars are composed of a continuous tube, S, said tube being bent at the ends of the furnace and brought back and forth between the solid grate-bars, as shown. In this case the cold water can be passed in at 80 either end of the pipe, but preferably at the end T, and after passing through the entire length of the pipe it is discharged into the boiler through the end V.

85 It will be noticed that in both of the constructions shown the solid grate-bars alternate with the tubular or water bars, and that by a slight shaking or rocking of the bars the entire surface of the grate, which includes the water-bars, is kept free from clinkers and 90 ashes, while the water in its passage through the hollow bars is heated and pumped into the boiler. The solid bars G are provided with pinion-wheels A', which mesh with each other, one of said bars being provided with an 95 100

arm or lever, B', by means of which the bars G can be rotated to free the grate of ashes and clinkers.

This construction or arrangement is especially desirable for locomotive-engines, as it enables the fireman to keep his fires clean with but very little exertion.

Having thus described my invention, what I claim, and desire to secure by Letters Patent, is—

In a furnace for steam-boilers, the grate which is composed of a series of hollow bars

for the circulation therethrough of water, and a series of solid bars arranged alternately with the water-bars, said solid bars being 15 adapted to be revolved or shaken, as and for the purpose set forth.

In testimony whereof I affix my signature in presence of two witnesses.

JOHN ASHCROFT.

Witnesses:

W. J. G. BEARNS,
AUGUST FISCHER.
